CLAIM

The ornamental design for a tire lifting and handling tool, as shown.

DESCRIPTION

FIG. 1 is a perspective view of the tool showing our new design;

FIG. 2 is a front elevational view thereof;

FIG. 3 is a right elevational view of the tool as shown in FIG. 2, the left elevational view being the mirror image of FIG. 3;

FIG. 4 is a rear elevational view of the tool as shown in FIG. 2;

FIG. 5 is a top plan view of the tool as shown in FIG. 4; and,

FIG. 6 is a bottom plan view of the tool as shown in FIG. 4.
